UNITED STATES PATENT OFFICE.

AXEL LUDVIG OLSON, OF ESSEX, CONNECTICUT.

LAMP.

SPECIFICATION forming part of Letters Patent No. 689,113, dated December 17, 1901.

Application filed January 25, 1901. Serial No. 44,701. (No model.)

To all whom it may concern:

Be it known that I, AXEL LUDVIG OLSON, a citizen of the United States, and a resident of Essex, in the county of Middlesex and State 5 of Connecticut, have invented a new and Improved Lamp, of which the following is a full, clear, and exact description.

This invention relates to a lamp the flame of which is supplied by a gas generated from 10 a hydrocarbon oil, preferably gasolene, by means of heat derived from the burner or burners of the lamp. To this end I employ a gasolene-reservoir with a peculiarly arranged siphon-tube, serving uniformly to deliver 15 the gasolene to a retort having baffle-cups, serving to atomize the oil, and in which retort the gasolene is vaporized by the heat from a tube passing through the retort, such tube conducting the hot gas from the lamp-burner. From the retort the gas is led to the 20 burner of the lamp and there consumed.

This specification is a specific description of one form of the invention, while the claims are definitions of the actual scope thereof.

25 Reference is to be had to the accompanying drawings, forming a part of this specification, in which similar characters of reference indicate corresponding parts in all the views.

Figure 1 is a vertical section of the invention. Fig. 2 is an enlarged vertical section showing the upper portion of the retort and a slightly-modified construction of the devices in the vicinity thereof. Fig. 3 is a plan view of the upper end of the hot air or gas tube which passes through the retort. Fig. 35 4 is a detail view of the flame-expander of the burner, and Fig. 5 is a side elevation of the drip-cup which is attached to the lower end of the air-tube.

40 Referring to Fig. 1, *a* indicates the retort, which is in the form of a vertically-disposed tube having a cap *a'* at its upper end. This cap has a nozzle *a²* delivering the gasolene or other oil into the retort, and the upper portion of this nozzle carries a pipe *b'*, passing from the oil-reservoir *b* and having a needle-valve *b²* therein commanding the flow of oil from the reservoir. Within the reservoir *b* is arranged a siphon *b³*, which communicates 45 with the tube *b'*, this siphon having its receiving end in the lower part of the oil-reservoir, so that the oil will be delivered to

the tube *b'* at a uniform pressure not affected by the volume of oil within the reservoir. A hanger or bail *b⁴* is attached to the upper 55 end of the nozzle *a²*, and by means of this hanger the whole apparatus may be supported, as Fig. 1 indicates. The lower portion of the retort *a* is enlarged, as indicated at *a³*, and from this enlarged portion of the retort *a* pass pipes *a⁴*, commanded by valves *a⁵* and leading, respectively, to the burners of the lamp. These burners are here shown to be two in number, one for each of the pipes *a⁴*, and the burners comprise tubes *c*, having 60 gauze covers *c'* at their upper ends. To these covers are attached by riveting or otherwise the tapered or conical flame-expanders *c²*, which are situated centrally of the burners and serve to throw the flame outward against 65 the incandescent mantles, one of which is indicated at *c³* in Fig. 1. These mantles are adapted to be held in the usual manner by rods *c⁴*, supported on the burners. Attached to each tube *c* is an annular holder *d* for the 70 chimneys *d*, and these chimneys may also be fitted with shades *d²*, as shown, all of which is of the usual construction. For the admission of atmospheric air into the chimneys *d* in the vicinity of the burners I form the 75 holders *d'* with orifices *d³*, as shown at the right-hand side of Fig. 1.

Located over the chimneys *d* are concavo-convex collectors *e*, which are loosely mounted on the ends of tubes *e'*. These collectors 85 may be moved on the tubes to the position indicated at the right-hand side of Fig. 1, so as to facilitate the emplacement or displacement of the shades *d²*. The tubes *e'* curve upwardly and inwardly and pass through the 90 cap *a'* of the retort *a*, where they are joined together and communicate with a tube *e²*, which passes down centrally through the enlarged lower end *a³* of the retort, the tube *e²* discharging at its lower end into a sort of 95 drip-cup *e³*, attached to the tube by hooks *e⁴*, carried by the cup and engaged with pins *e⁵* on the lower end of the tube *e²*. This cup *e³* does not obstruct the passage of air or gas through the lower end of the tube *e²*, but it 100 will collect any liquid material which may fall from the tube. Attached to the tube *e²* at points within the retort *a* are cups *e⁶*, which serve to baffle the flow of the oil down

the retort, and in thus retarding the oil to accelerate the vaporization thereof.

In the operation of the device upon opening the valve b^2 the oil will flow into the retort a , and being first vaporized therein by passing over the baffle-cups the vapor may then be burned at the burner c , and the hot gases passing out at the chimney d will be held by the collector e and forced to pass through the tubes e' and down through the tube e^2 , thus heating the retort a and insuring the complete vaporization of the oil. Air is mixed with the gas in the retort, the air flowing through openings a^6 in the retort a . These openings are arranged in the upper portion thereof and may be regulated in point of size by an annulus a^7 adjustably fitted on the exterior of the retort. The gas generated in the retort may pass by the limbs a^4 thereof to the burners, and the burners are thereby supplied. It will be observed that by this arrangement the gas is consumed as fast as it is generated and that it is not stored under pressure in any part of the apparatus. The heat of the burner is utilized to gasify the oil, and there is no danger of explosion of any of the parts, since the flame of the burner is entirely removed from the retort a and reservoir b .

Figs. 2 and 3, illustrating a slight modification of the structure at the upper end of the retort, show a cap f , which is similar to the cap a' before described. This cap has the tubes e' entered thereinto and passed into a cap f' , which is adapted to fit over the upper end of the tube e^2 . The upper end of the cap f has a boss f^2 attached rigidly thereto, and this boss carries a nozzle f^3 , similar to the nozzle a^2 . The boss f^2 also has the lower portions of the limbs of the bail or hanger b^4 attached thereto by which to support the lamp, such attachment being effected through the medium of set-screws f^4 , as shown.

Having thus described my invention, I claim as new and desire to secure by Letters Patent—

1. A lamp, comprising a vertically-disposed tubular retort, a tube concentric to said retort for the purpose of heating the same, and spaced baffle-cups located outside

of said tube and inside of said retort, and means for supplying said cups with a volatile combustible liquid.

2. A lamp, comprising a retort, a tube located inside of the same for supplying heat thereto, a plurality of annular baffle-cups surrounding said tube and spaced from each other, and means for supplying a volatile combustible liquid to said baffle-cups.

3. A lamp having a vertically-elongated retort, a cap secured to the upper end thereof, a fuel-reservoir mounted on the cap and delivering the fuel thereinto, burners arranged at the side of the retort, tubes passing from the lower end of the retort to the burners, and tubes arranged over the burners to carry off the heated products of combustion therefrom, said tubes passing through the cap at the upper end of the retort and downward out of the lower end thereof, for the purpose specified.

4. A lamp, comprising a central tube provided with means for passing hot gases through the same and also provided upon its exterior with annular baffle-cups, an outer tube concentric with said central tube and provided with air-inducts, means for supplying hydrocarbon liquid to said central tube and said baffle-cups, and a burner connected with said outer tube for consuming aerated hydrocarbon vapor.

5. A lamp, comprising a central tube provided with baffle-cups, a burner connected with said central tube to supply the same with hot gases, a plurality of annular baffle-cups mounted upon said central tube and heated thereby, an outer tube concentric with said central tube and baffle-cups, and provided with air-inducts, a member connecting said outer tube with said burner for supplying the latter with combustible vapor, and means for feeding hydrocarbon liquid to said central tube and said baffle-cups.

In testimony whereof I have signed my name to this specification in the presence of two subscribing witnesses.

AXEL LUDVIG OLSON.
